(57) **CLAIM**

The ornamental design for a buckle, as shown and described.

DESCRIPTION

FIG. 1 is a front perspective view of a buckle showing my new design;

FIG. 2 is a front elevational view;

FIG. 3 is a left side elevational view, the right side elevational view being a mirror image thereof;

FIG. 4 is a rear elevational view;

FIG. 5 is a bottom plan view;

FIG. 6 is a front elevational view of the upper portion of the buckle, the lower portion has been removed for ease of illustration;

FIG. 7 is a rear elevational view of FIG. 6;

FIG. 8 is a front elevational view of the lower portion of the buckle reduced in scale for illustrative purposes, the upper portion has been removed for ease of illustration shown;

FIG. 9 is a rear elevational view of FIG. 8, shown slightly enlarged;

FIG. 10 is a rear elevational view of the front segment of the lower section of the buckle shown in FIG. 8, shown slightly enlarged;

FIG. 11 is a rear elevational view of the back segment of the lower section of the buckle of FIG. 9, shown slightly reduced in scale;

FIG. 12 is a rear perspective view of FIG. 1;

FIG. 13 is a rear perspective view of FIG. 12, shown partly disassembled and slightly reduced in scale for ease of illustration; and,

FIG. 14 is rear perspective view, the front and rear segments have been illustrated partly disassembled and the upper section of the buckle removed for ease of illustration.
